Primary Examiner — Sandra S Snapp*Assistant Examiner* — Katherine Glennon(74) *Attorney, Agent, or Firm* — Abelman, Frayne & Schwab(57) **CLAIM**

The ornamental design for a watch crown, as shown and described.

DESCRIPTION

FIG. 1 is a front view of a watch crown showing the new design;

FIG. 2 is a rear view thereof;

FIG. 3 is right side view thereof;

FIG. 4 is a left side view thereof;

FIG. 5 is a top view thereof;

FIG. 6 is a bottom view thereof;

FIG. 7 is a front, right, and top perspective view thereof; and,

FIG. 8 is a rear, left, and top perspective view thereof.

The portions of the watch crown shown in broken lines form no part of the claimed design.

1 Claim, 3 Drawing Sheets(56)
